PAIR OF BINOCULARS OR THE LIKE

Paul R. Maguire, Los Angeles, Calif., assignor to David P. Bushnell, Pasadena, Calif.

Application November 25, 1957, Serial No. 48,618

Term of patent 14 years

(Cl. D57—1)

Figure 1 is a perspective view of a pair of binoculars or the like, showing my new design;

I claim:

The ornamental design for a pair of binoculars or the like, substantially as shown.
